UNITED STATES PATENT OFFICE.

AXEL G. ANDERSON, OF CHICAGO, ILLINOIS.

DRILLING MACHINE.

Application filed June 25, 1921. Serial No. 480,273.

To all whom it may concern:

Be it known that I, AXEL G. ANDERSON, a citizen of Sweden, residing at Chicago, in the county of Cook and State of Illinois,

5 have invented certain new and useful Improvements in Drilling Machines, of which the following is a specification.

My invention relates to drilling machines, and has particular reference to hand, or so 10 called "breast drills." The object of my invention are to provide improvements in the jointed types of these machines for the purpose of enlarging their scope of operation, lessening their cost, and simplifying the

15 mechanism while at the same time giving increased adaptability and serviceability in situations and places to which access may not be had by former constructions; to provide a construction of increased commercial 20 practicability, or which is available to the average user instead of being limited to those only who can afford to purchase the more expensive machinery and tools; to provide a machine with an articulated frame 25 and rotary spindle that provides sections which are adjustable angularly relative to the plane of rotation of the main driving gear and to each other, one of said sections being confined, substantially, to the

30 chuck-end of the machine body, or in which substantially only the drill or bit itself, may be inclined to said body without moving the major portions out of their usual alignments; to provide a construction and arrangement 35 in which the drill, or its substitute, is operative laterally to the main spindle, and yet in parallel relation thereto, to, substantially, the extent of the throw of the operating crank or handle or the radius

40 of the driving gear, and which may also be aligned or arranged concentrically with the main spindle as in the old or conventional constructions; to provide facilities for operating the drill or bit when pointed toward 45 as well as away from the operator, for the purpose of gaining access to otherwise inaccessible places, and to provide such other advantages and facilities as will appear from the novel combination and arrangement

50 of parts hereinafter described in detail, illustrated in the accompanying drawing and more particularly pointed out in the appended claims.

In the drawing—

55 Figure 1 is a side elevation of an embodiment of my invention.

Figure 2 is a similar view taken in a vertical plane at right angles to the plane of Figure 1, and showing the jointed sections in changed positions. 60

Figure 3 is a section taken substantially on the line 3—3 of Figure 1.

Figure 4 is a reduced view showing the chuck-carrying section reversed to place its spindle section in alinement with the other 65 sections of the driving spindle or shaft.

In the several views the usual gears and spindle supporting frame is divided into three sections 2, 3 and 4 with pivoted yoke or fork portions in which the bevel or miter 70

gears are mounted. The section 2 carries in the usual or any preferred manner the customary main driving gear or wheel 5 provided with a fixed or adjustable handle or crank 6. The section 2 is provided with a 75 forked portion with arms, branches or horns 7 and 8 which terminate in pivot-bearing lugs 9 and 10 which are pivoted to lugs 11 and 12 on a widened and bifurcated portion of the section 3 on a pivot 13 80

at one side and a similar pivot 14 at the opposite side. The section 3 is of skeleton form with an opening 15 therethrough for an intermediate spindle 16 which has its journal-bearings at 17 and 18 at the ends of 85 the transverse opening 15. To the lower end of said intermediate spindle section 16 is keyed, as at 19 (Fig. 3) a hemispherical gear wheel 20 in the upper or plane side of which is a depression 21. To the upper end 90

of the spindle 16 is keyed a bevel gear or pinion 22 and from its spindle bearing portion 17 projects bearing arms or posts 23 and 24, the latter having an inwardly enlarged portion, or bearing-lug, 25 in which 95

and the part 23 is supported a pivot-spindle 26. On the latter is revolvably mounted a wheel with gear teeth 27 and 28 on its respective sides or faces. The teeth 28 are arranged to mesh with the teeth 100

on the pinion 22 and the teeth or cogs 27 mesh in a similar manner with a bevel pinion 29 which is keyed to a chuck-carrying spindle 30 journaled in a bore made for it in the section 4. The spindle section 30 has 105 an end-thrust bearing 31 in a bearing-lug 32 on an arm, or fork-portion, 33 on the frame-section 4. A substantially similar arm or fork portion 34 projects from the opposite side of the section 4 and the lower 110 end of the latter arm or fork portion is mounted on the pivot spindle 26.

On the end of the horn or fork portion 10 and arranged at right angles to the main driving gear 5 is a quadrant-like plate 35 in which is an arc-shaped slot 36 which is concentric with the bearing lugs 11 and 12. The arc-slot 36 is shown engaged with a bolt or screw 37 which has threaded engagement as at 38 with one of the wings of the enlarged or fork portion of the frame-section 3. By tightening the head of the screw or bolt 37 against the plate 35 the sections 2 and 3 will be held immovably relative to each other either in normal alinement or at any adjusted angular relation. 10 While the simple screw or bolt arrangement is shown in connection with the part 35, other of the many well known locking devices for this purpose may be employed to effect relative immovability of the parts 2 and 3. 15

A substantially similar arrangement for preventing movement of the parts or frame sections 3 and 4 on the pivot-spindle 26 is provided in the form of an open ring 39 arranged around the periphery of the double gear wheel 27-28. This ring, which functions in substantially the same manner as the plate 35, has its ends secured by soldering or otherwise at 40 and 41 to the opposite sides of the section 3. A set-screw, or bolt, 42 is brought to bear against said ring, and has engagement with a threaded bore in the arm 34, but other suitable equivalent means may be employed for holding the parts 3 and 4 in fixed relation to each other. 30

As shown in Figures 1 and 2 the frame-section 4 is offset to one side of the section 3, but with its shaft 30 substantially parallel to the shaft or spindle 16 when the parts are in normal position, or as in Figure 1. This offset, or lateral arrangement, is serviceable in drilling a hole close to and parallel with a wall or surface which would come within the path of rotation of the driving gear 5 were the shafts or spindles 16 and 30 alined. 40 The substitution of the parallel offset where available gives the operator approximately the same power or purchase on the machine that would be had with the spindles 30 and 16 alined, which power or purchase must be sacrificed to some extent where the drilling is made with the section 4 adjusted angularly on its pivot 26 and where in many cases auxiliary support must be provided in applying pressure to the drill. 45 However in all cases more stability is had and less "purchase" on the machine is lost where the angular adjustment takes place near the drill than where it is had at or near to the axis of the driving gear 5. In the present arrangement even the axis 11 and 12 between the frame-sections 2 and 3 is removed from the axis of the wheel 5 as to leave that part of the frame intact which carries the main driving gear and its operating handle 50

by the provision of the hemispherical gear 20 which has its swinging axis (11-12) at the periphery of the large driving gear 5. As shown in Figure 2 the hemispherical gear wheel or pinion 20 will operatively mesh 70 with the teeth on the wheel 5 at a great variety of angles of inclination up to a position where its axis of rotation is approximately at right angles to the plane of rotation of the wheel 5. When thus adjusted and the parts 3 and 4 arranged at right angles to each other as in Figure 2 a hole may be drilled in the direction of the operator of the machine by pulling instead of pushing upon it, and, of course, if considerable resistance is offered to the work of the drill auxiliary means for bringing pressure against the drill would be employed and such expedients would be determined by the special conditions surrounding the work to 75 be done by a breast drill as distinguished from the predetermined situations for which the larger and permanently mounted drilling machines are provided. 80

In Figure 4 the section 4 is shown reversed to place the spindles 30 and 16 normally in alinement, or the pinion 29 over the pinion 22 and both meshing with the gear teeth 28, instead of one pinion meshing with one side of the double gear wheel 27-28 95 while the other meshes with the other side. This makes the drill substantially the same as the ordinary breast drill in that the driven spindle is practically continuous from the driven gear 20 to the chuck 43. 100

Having thus described my invention I claim as new and desire to secure by Letters Patent—

1. In a breast drill, the combination in a frame consisting of three pivoted together sections having their pivots arranged at right angles to the axis of the main driving gear, of a plurality of spindle sections each of which is provided with intermeshing pinions operable at different angles of inclination of said spindle sections, and means for holding said sections fixedly in their adjusted positions. 105

2. The combination with a breast drill having a driving and driven gear, a spindle rotatably mounted and angularly adjustable in said frame relative to and to be rotated by said driving and driven gear, of a chuck-carrying section pivotally connected with said frame, said chuck-carrying section having a comparatively short rotary spindle, pinions operatively connecting said first mentioned spindle and short rotary spindle, and means for adjusting and holding in the adjusted position, at different angles of inclination relative to the main spindle, said short rotary spindle. 115

3. In a breast drill, the combination of a frame consisting of three pivoted together sections, the first of which, or the main driv- 120

ing wheel section, carrying the driving gear wheel while the remaining sections carry rotary spindles with pinions keyed thereto and meshing with, respectively, the driving gear wheel and with each other, with a hemispherical gear wheel, meshing with said driving gear wheel, means for adjustably supporting the axis of rotation of said hemispherical gear wheel at an inclination to the axis of rotation of said main driving gear wheel, and means for similarly adjustably supporting the second and the third of said frame sections.

4. In a breast drill the combination of a spindle-carrying frame in three sections, the first of which carries the usual driving gear and the last the chuck, said first and last sections being movable parallel with but laterally to the long axes of the remaining sections, and means for adjustably holding said sections at variable inclinations to each other at right angles to their plane of parallelism.

In testimony whereof I have hereunto signed my name.

AXEL G. ANDERSON.
